UNITED STATES PATENT OFFICE.

CHARLES W. WILSON, OF YORK, PENNSYLVANIA.

PROCESS AND APPARATUS FOR MAKING PHOTOGRAPHIC PRINTS.

1,353,690.

Specification of Letters Patent. Patented Sept. 21, 1920.

Application filed June 21, 1917. Serial No. 176,212.

To all whom it may concern:

Be it known that I, CHARLES W. WILSON, a citizen of the United States, and resident of York, Pennsylvania, have invented certain new and useful Improvements in Processes and Apparatus for Making Photographic Prints, of which the following is a specification.

It is the object of my invention to provide apparatus for modifying the characteristics of photographic negatives in printing therefrom, so that the printing effect can be retarded or advanced at any desired portions of the negative for the purpose of bringing out the details as is well understood by those skilled in the art, it being necessary in this connection to tone-down certain parts of the negative for the best printing effect.

In carrying out my invention the negative is left untouched, the modifying material being applied to a member arranged over the face of the negative and which may be repeatedly used.

The invention consists in the features and combination and arrangement of parts and in the steps of the method as will be hereinafter described, and particularly pointed out in the claims.

In the drawings:

Figure 1 is a sectional view of a printing frame used in carrying out my improved method with the retouching or toning-down element associated therewith.

Fig. 2 is a rear view of the printing frame.

Fig. 3 is a longitudinal section of the apparatus.

Fig. 4 is a perspective view of the apparatus.

Figs. 5 and 6 are detail views relating to the apparatus.

In these drawings 1 indicates the main part of the printing frame which may be of substantially ordinary form in so far as it consists of a rectangular open frame member. This member on its rear side is provided with upstanding marginal flanges 2 extending along each of its lateral sides, providing a tray-like receptacle for receiving the back of the frame, which includes a head portion 3 and side strips 4, hinged or pivotally connected thereto and a central swing-back member 5, 5', also hinged and pivotally connected with the head portion 3. The side strips 4 as well as the swing-back

5 may be secured to the main part 1 by catches. There is one of these catches 6 for each of the side strips and one 6' for the central member 5', so that these may be manipulated independently. The whole back member, including the head 3, is movably or removably connected with the main part of the frame 1 in any suitable manner.

In the drawing it is shown as removably held by clamps 7 pressed by springs 7', the clamps working in brackets 7" on the main frame. These clamps can be released by grasping the buttons 7" and lifting them and they may be held released by turning them so that the pins 7" will rest on top of the brackets out of line with the slots 7" in which the pins work. The whole back of the frame may be removed. These back members 3 and 4 overlie the rear face of the 75 strips composing the main frame so as to clamp the negative in place and the swing-back is adapted to clamp or hold in place the sensitized paper which is to be printed.

It will be noticed that the swing-back is 80 in sections 5, 5' hinged together at 5" and the forward section 5' may be raised without raising the section 5, as illustrated in Fig. 4, a leaf spring 5" being secured to the cross piece 3 and having its front end engaging a loop 5" on the section 5', this spring lifting both sections 5, 5' when they are free.

The section 5 may be held down to clamp the film or negative by the clips 5" while 90 the section 5' is free to be lifted. When the catch 6 of section 5 is engaging the lug 6' on the main part of the frame both sections 5, 5' will be securely held.

Strips a are arranged along side of the 95 swing-back and between the same and the strips 4, and strips a may be locked either to the swing-back section 5' to move therewith as one body or they may be locked to the strips 4. For this purpose locking clips 100 d are provided pivoted at d' to the strips a and adapted to engage notches x, y in the parts 5 and 4 respectively to lock the strips a either to the swing-back or to said strips 4.

The frame is adapted to hold either negative of the ordinary glass form or films and if films are used the strip may be disposed lengthwise of the frame as shown at A, Fig. 3, or cross wise of the frame, as shown at B. When disposed lengthwise the film strip is 110 run through an opening e of the main frame and is clamped by the back of the frame

along the portion to be printed and for holding the film at the front end of the frame, I provide a spring clamping member 5 extending into the opening *e* and clamping the film against the wall of said opening.

To permit the film to be inserted cross-wise lateral openings or slots are provided in the sides of the main frame at *g*.

- 10 In carrying out my process of retouching or modifying the characteristics of the negative I employ a plate 10 or a sheet of material as tissue paper or tracing linen may be used. The plate may consist of glass having a ground surface 10' on one face or a sheet of celluloid or fibroid may be employed, likewise having one face having the characteristics of a ground glass surface, and adapted to receive markings or material 20 which will act to restrain the passage of light at the points where said material is applied. This ground glass plate or sheet having a surface answering the purpose of a ground glass surface is placed in the printing frame with its ground surface directed outwardly. This is so placed and is of such dimensions that it will be held by the head and side strips of the back of the printing frame but before clamping these parts in 25 place the negative or film A is next placed in position upon the inner face of the tone-modifying plate or sheet, the negative having its film face directed inwardly or toward the back of the printing frame. The head 30 and side strips of the back are then clamped in position to securely hold the negative and the toning-down or modifying sheet in fixed relation to each other or in other words to prevent any movement of these parts 35 relative to each other. By holding the frame to the light with its back section 5, 5' in open position and with the ground glass face toward him the retoucher can determine what parts of the negative require to be 40 modified in order to get the best printing results and he then applies the toning-down or modifying material to the ground glass or similar face as his artistic sense may dictate. This toning-down material may be of 45 various kinds, for instance burnt umber powder, yellow ocher, powdered crayon or Prussian red or any other suitable powder may be employed or the artist may use lead pencil of any desired degree of hardness or 50 crayon may be used. In fact any powdered material may be employed which will have a retarding effect on the passage of the light. The artist may apply the powder by rubbing it on by his finger or by a stump or 55 pad of any suitable nature. By reason of the fact that the outer face of the modifying plate or sheet is of a ground glass nature the powder or pencil or whatever material may be used in dry form will adhere to the 60 surface without requiring paste or a mix- 65

ture of any adhesive to the toning-down material and it may be rubbed off as conditions may require and as the proof prints may dictate and any suitable instrument, such as an ordinary rubber eraser may be 70 used in the rubbing off process, or the dry finger of the operator may be used.

If it is desired to make any portions of the negative receive more light than others an oily or greasy substance may be applied by 75 the artist by rubbing it on with his finger or with a stump or camel hair brush, such for instance vaseline, glycerin, butter or lard. The application of material of a greasy character will make the portions of the 80 ground glass modifier more transparent at the points where it is applied and this may be used at one point while the powdered restraining or toning-down material may be used at another point.

85 After having applied the toning-down material to the modifying plate or sheet the operator may place the sensitized paper on the negative and then clamp down the central member or swing-back 5 to hold the 90 paper in proper position, it being understood that during the time the artist is retouching or in other words applying the toning-down or modifying material to the modifying sheet or plate the back has been 95 held in open position to permit the passage of light through the negative and modifying plate so that the artist could properly apply the toning-down or modifying material.

100 After having clamped the sensitized paper in place the printing is done in the ordinary way by exposing the paper with its superimposed film or plate forming the negative to the light, it being understood that the modifying plate with the toning-down material applied thereto remains in place and thus modifying the passage of light to the negative and thence to the sensitized paper.

105 It will be observed that the negative and modifying plate are in direct contact but 110 their surfaces are directed oppositely, that is to say the ground glass surface is directed outwardly in respect to the front of the frame, whereas the film surface of the negative is directed toward the rear, thus lying 115 in proper position to receive the sensitive paper directly in contact therewith.

120 It will be observed that I employ the same frame for holding the negative and sensitized paper and also the modifying plate or sheet and that this frame is of a special form due to the necessity of holding the negative in a definite position in relation to the modifying plate or other member 10, it being possible to open the back for the 125 placing of the sensitized paper while insuring the maintenance of the registry of the negative and the modifying member.

130 It will be observed that it is of special advantage to employ powdered material of

the characters described as no proportioning and mixing of materials by the artist is necessary and their character being fixed he does not have to make a mixture of any sort 5 and consequently the care in selecting and proportioning, as well as mixing ingredients, is entirely avoided and no special tools are required, either in applying the powder or in removing it. The modifying 10 plate or sheet of course may be repeatedly used, the special frame holding this and the film or negative while the back is opened for the insertion of the paper.

By placing the modifying member directly in contact with the negative a proper 15 transmission of the light may be secured for the best effect, the diffusion of light being kept down to the proper degree by using a plate or sheet of suitable thickness and by 20 employing these parts in contact.

Different degrees of sharpness in the printing may be obtained by using modifying plates of different thicknesses and of course by applying the modifying material 25 in different degrees of thickness of the layer.

The modifying plate or member if in the form of glass or like rigid or inflexible material will serve as the front to hold in place the negative should this be in film form, 30 thus this modifying plate performs the two-fold function of modifying the passage of light and also as a holder for the film when this is used.

It will be understood that the printing 35 frame described is essential because it is necessary to hold the negative in a fixed relation to the modifying member while permitting the removal and insertion of the sensitized sheets to be printed upon, and this 40 is true whether the negative be in plate form or in the form of a film, or whether this film be disposed transversely of the frame or longitudinally thereof. The clamping member *f* will hold the film in position while 45 the back of the frame is opened or is manipulated to put in successive paper sheets for printing and if the film is run crosswise the side strips *4* will hold the film while the swing-back is manipulated for placing or 50 removing the sheets to be printed, and it will be observed that a plurality of strips may be threaded across the frame, as indicated in Fig. 4. The supplemental strips *a* enable the operator to make different sizes 55 of prints while the negative or film is held in fixed registry with the modifying member because these strips *a* may be attached to the swing-back to move therewith and thus enlarge the space for receiving the 60 printing paper or by attaching these strips to the side strips *4*, the space to receive the printing paper is reduced. Furthermore, the sections *5'* of the swing-back may be 65 swung up independently of the section *5* while the printing paper is held by the lat-

ter so that the printing paper may be turned up and inspected to show the progress of the printing or exposing action.

Further I show at *Z*, Fig. 2, clips attached to the underside of the side strips *4* to hold 70 films which are cut from the strip and are too small to reach from one clamping strip to the other. These clips will enable the operator to carry on the work because the negative or film will be held in fixed relation to the modifying sheet or member at all 75 times and the operator by opening the back can touch up upon the modifying member and any number of prints can be made without danger of disturbing the modifying member and negative relative to each other. This is most essential because if the registry between modifying member and negative does not remain absolutely fixed while the printing is being done and the paper is being 80 inserted and removed, the retouching would have to be done over again for each exposure.

In other words, while I employ a modifying sheet or member as an element separate 90 from the negative, these two parts are maintained in fixed registry and practically as one member while the operator is permitted to make any number of prints and prints of various sizes, and the negative may be in 95 the form of a plate or a roll film, or a cut film. At 5", Fig. 2, I show a clip for holding the two members of the swing back so that they will move as one.

The catches *6* and *6'*, it will be noticed, 100 are of different forms in respect to each other, the one shown at *6'* having a finger piece overhanging the central member *5'* so that by pressing on this finger piece the catch will be released, this action resulting 105 from the outward movement of the lower engaging end of the catch due to the catch as a whole acting as a lever fulcrumed at an intermediate point of its length. The catches *6* are arranged with outwardly extending 110 finger pieces and in order to release these catches the central portion of the catch member is pressed downwardly while at the same time, the finger piece is pressed upwardly. This action can be performed 115 by the thumb and finger of one hand, the finger pressing upon the main middle portion of the catch member while the thumb exerts a lifting force underneath the finger piece. These differences between the catches 120 *6* and *6'* will enable the catches *6* to hold the sections of the back in proper position with the film properly clamped when the frame is reversed to do the retouching on the ground glass surface because pressure on 125 the finger pieces of the catches *6* due to the frame resting on its back will not have any tendency to release these catches, but on the contrary, will tend to force them more securely into their holding relation.

In using the frame for retouching, it is customary to set it up, using the central portion of the hinged back as a prop and the clamps which hold the sides of the swinging back serve as supporting feet for the frame when thus set up. The form of these side clamps or catches is such that the weight of the frame or the force applied to the frame in retouching the modifying member does not affect the holding quality of these clamps because pressure upon their extreme ends, exerted toward the front of the frame, will not release them. If these side catches were of the same form as the center catch, they could not serve as supporting feet.

What I claim is:

1. In apparatus for printing from photographic negatives, the combination of a frame having a front portion and a movable back and a modifying member within the frame, backed by and resting against the film and having its exposed surface adapted to receive and hold modifying material, said member together with the negative and the paper to be printed being held by and between said front and back portions of the frame and said member serving as the outer retaining wall or layer at the front of the frame, substantially as described.

2. In apparatus for printing from photographic negatives, a frame having a front portion and a back in sections, a member held in said frame, together with and in fixed relation to the negative by a part of the sectional back and having a surface to receive material modifying the passage of the light to the negative and another section of said back holding the sensitized paper to be printed on, said latter section being movable in relation to the section which holds the modifying member and negative, whereby an opening for the passage of light will be maintained for touching up the modifying plate after which the sensitized paper may be clamped in place, substantially as described.

3. The apparatus herein described for making photographic prints comprising a main frame portion to receive a negative or film and a tone modifying member and a swing-back composed of a plurality of strips and a central hinged member with means for attaching certain of the strips to the swing-back member or to other strip members to increase or decrease the size of the space adapted to receive the printing paper while the negative and modifying member are held relatively fixed, substantially as described.

4. Apparatus for making photographic prints, comprising a main frame portion with a modifying sheet or plate, a back member having portions to hold a film extending either cross wise or lengthwise of

the frame and in fixed registry with the modifying member, said back having a hinged or swinging portion or portions which may be opened to receive the printing paper while the film is clamped in fixed registry with the modifying sheet or plate, substantially as described.

5. A printing apparatus comprising a modifying member, a frame having a back with side strips to hold the negative and modifying member and a swinging portion between them with strips intermediate the side strips and the central portion and hinged to the main part of the back with means for securing the intermediate strips either to the central swinging portion or the side strips to increase or decrease the size of the printing space without disturbing the fixed relation of the negative and the modifying member, substantially as described.

6. In a printing frame, a main member, a back, a modifying member held between the back and the main member of the frame, said main member having an opening to receive a film and a clamp for holding the film in said opening, said film being also held between the main portion of the back and the main portion of the frame and said back having a swinging portion to permit the placing or removal of printing paper while the film and modifying member are held in fixed registry, substantially as described.

7. The herein-described apparatus consisting of a modifying member, a frame holding the same in fixed relation to the negative and consisting of a main frame portion and a back portion, said back portion having a part or parts which hold the modifying member and the negative in fixed registry whether the negative be a plate, a film strip or a cut film, said back having a movable portion to clamp or permit the removal of the paper while the negative and modifying member are maintained in said fixed relation, substantially as described.

8. In apparatus for printing from photographic negatives, a frame having a front portion and a movable back, and a modifying member removably mounted within the frame and consisting of a rigid plate having its exposed surface adapted to receive and hold modifying material, said member together with the negative and the paper to be printed being held by and between said front and back portion of the frame, and said member forming the front retaining wall of said frame to hold the film and sensitized paper in place, substantially as described.

9. In combination in a photographic printing frame, a main frame portion, a back member formed in movable sections including a center section and two side sections, and a head portion to which said sec-

tions are hinged, a catch for each of the side sections for holding it at its free end to the front of the frame, each of said catches being releasable by pressure exerted thereon in a direction rearwardly from the back of the frame, said catches, therefore, being adapted to act as supporting feet for the frame when set up for modifying, and a catch for the center section, substantially as described.

10. In combination in a photographic printing frame, a main frame portion, a back member formed in movable sections including a center section and two side sections, and a head portion to which said sections are hinged, a catch for each of the side sections for holding it at its free end to the front of the frame, each of said catches being releasable by pressure exerted thereon in a direction rearwardly from the back of the frame, said catches, therefore, being adapted to act as supporting feet for the frame when set up for modifying, and a catch for the center section, said last mentioned catch comprising a resilient member having a catch end and a finger piece having a fulcrum portion to bear on the resilient member and release the catch end when the fin-

ger piece is pressed in a direction toward the front of the frame.

30

11. In combination in a photographic printing frame, a main frame portion, a plurality of hinged back sections, a catch for the central section adapted to be released by pressing down thereon, and catches for the adjacent side sections adapted to act as supporting feet for the frame when set up, and releasable by raising their outer ends, substantially as described.

35

12. In combination in a photographic printing frame, a main frame portion, a back formed in sections including a central and side sections, catches for holding the side sections, comprising spring members having a main portion, a downwardly extending engaging portion, and a finger piece extending forward of the engaging portion, said catch being adapted to be released by pressing down upon its main portion, and lifting upon its finger piece said side catches serving as supporting feet for the frame, and a catch for the center section, substantially as described.

40

45

In testimony whereof I affix my signature.
